UNITED STATES PATENT OFFICE

ELBERT A. CORBIN AND HERMANN ALBRECHT, OF PHILADELPHIA, PA.

IMPROVEMENT IN CLOTHES-WRINGERS.

Specification forming part of Letters Patent No. 140,249, dated June 24, 1873; application filed March 11, 1873.

To all whom it may concern:

Be it known that we, ELBERT A. CORBIN and HERMANN ALBRECHT, both of the city and county of Philadelphia and State of Pennsylvania, have invented Improvements in Clothes-Wringers, of which the following is a specification:

Our invention relates to improvements in the clothes-wringers for which Letters Patent No. 112,669 were granted to August Albrecht March 14, 1871, and reissued (No. 5,261) January 28, 1873.

The objects of our present improvements are, first, to insure a firm attachment of the machine to the edge of the tub, and, second, to impart increased steadiness to the frame.

The first object we attain by means of a plate, *d*, hung loosely to each frame, so as to accommodate itself to the edge of the tub *B*, which, by means of a screw, *h*, is gripped by and between the said loose plate and the leg *f* of the frame, all as shown in the side view, Figure 1, of the accompanying drawing. The second object we attain by a cross-bar, *H*, which connects the opposite frames together, as shown in the vertical section, Fig. 2.

As regards the general character of the frame-work, the levers *D*, and the springs *E* situated between the fulcrums of the levers and the roller *G*, our improved wringer is very similar to that described in the said re-issued patent of August Albrecht.

The plate *d* before referred to as being loosely hung to each frame is, in the present instance, so connected to a fixed rod, *g*, in a recess of the said frame that it can slide to and fro, as well as vibrate freely thereon, and hence can accommodate itself to the side of the tub *B*, shown by dotted lines in Fig. 1, when the screw *h* is tightened, the extended surface of the plate insuring a firm hold of the machine on the tub.

In the said reissued patent the opposite

frames were connected together through the medium of the rollers only, but we have found that increased steadiness can be attained by a light cross-bar, *H*, one end of which is confined between the rubber spring *E* and lever *D* of one frame, and the opposite end between the spring and lever of the opposite frame, no preparation being made to secure the bar other than a slight projection, *z*, on each lever adapted to a hole in the bar.

The dirty oil which, in ordinary wringers, escapes from the bearings frequently soils the clothes, an evil which we obviate by the use of wood bearings, illustrated in Fig. 3, these bearings being so prepared by boiling in oil or its equivalent, or in a mixture of oil and paraffine, that no other lubrication is required for the journals of the rollers than a little soap and water, which can be taken from the wash-tub and applied from time to time.

The inclination of the leg *f* is such in respect to a line, *y*, drawn through the centers of the rollers that, when the machine is clamped to the tub, the rollers will project so far toward the interior of the same that the splashing of water and suds over the edge of the tub is prevented.

We claim as our invention—

1. A clothes-wringer in which a plate, *d*, to be acted on by a screw, is hung loosely to and arranged to slide freely on each frame, and is combined with the jaws of the same, as and for the purpose set forth.

2. The combination with the opposite frames and levers of a cross-bar, *H*, confined at the ends, substantially in the manner described.

In testimony whereof we have signed our names to this specification in the presence of two subscribing witnesses.

E. A. CORBIN.

Witnesses: HERMANN ALBRECHT.

WM. A. STEEL,

JOHN K. RUPERTUS.
